UNITED STATES PATENT OFFICE.

CLARENCE A. BERKINS, OF MINNEAPOLIS, MINNESOTA.

HYDROCARBON BURNER.

Application filed June 25, 1924. Serial No. 722,279.

My present invention provides a simple and highly efficient oil or hydro-carbon burner adapted for general use in furnaces, boilers, stoves and the like, and which is 5 capable of easy adjustment to fire pots of different sizes, which require a greater or less amount of generated oil vapor.

Generally stated, the invention consists of the novel devices and combinations of devices hereinafter described and defined in the claims.

The commercial form of the improved burner is shown in the accompanying drawings, wherein like characters indicate like 15 parts throughout the several views.

Referring to the drawings:

Fig. 1 is a vertical section taken through the burner and a portion of the grate structure; and 20 Fig. 2 is a plan view of the lowermost member of the stock of dished annular generating plates, showing the same removed from the burner.

The improved burner, as designed, comprises a box-like base member 3, a plate 4 mounted as a cover on the base, a goose-neck air delivery tube 5, and a stack of dished annular generating plates, the structure of which latter will be presently described.

The box-like base 3 has a transverse partition 6 that divides the same into an air intake chamber 7 and a dead air chamber 8. The cover plate 4 is preferably flanged so that it rests in proper position on the top 35 of the base 3, and above the dead air chamber 8, there is formed a generating bowl 9 having at its axis an upstanding hub 10 preferably of conical form. The bottom surface of the bowl, surrounding but con-

siderably outward of its hub 10, is provided with circumferentially and radially spaced upstanding combined heat-radiating and gas-reflecting pins 11 preferably cast integral therewith. An oil or fluid fuel supply pipe

45 12 leads upward through the compartment 8, is tapped through the hub 10 and extended considerably above said hub, and at its upper end is threaded at 13. The pending delivery end of the large goose-neck air tube 5 is terminated slightly above the horizontal plane of the upper edge of the bowl 9 but is located concentric to the axis of said bowl and its hub 10. The

numeral 14 indicates an oil overflow pipe, which leads from the bowl 9 at a point below its rim but above its bottom. 55

The device herein treated as the generating device proper is, as already indicated, made up of a plurality of dished annular generating plates, the number of which may 60 be varied to suit the requirements of the particular fire pot in which the burner is to be installed. As shown in the drawings, it comprises three such generating plates, the lower of which is indicated by the numeral 15, the upper by the numeral 16, and the intermediate by the numeral 17. The lower generating plate 15 has a depending annular flange that rests on the bottom of the bowl 9 and freely surrounds the hub 10 70 thereof, and said plate 15 is provided with an upstanding annular aligning hub 18 preferably made conical. The plate 17 is in the form of a link that fits loosely around the aligning hub 18 and rests on a shoulder 75 formed adjacent to the base of said hub, and just outward of which shoulder, said lower plate 15 is formed with a dished annular oil-receiving channel 19. The upper plate 16 closes the opening in the aligning 80 hub 18 and its lower portion is recessed so that it is nested over the upper end of said hub and preferably rested upon the hub portion of the intermediate plate 17. The upper surface of said plate 16 is dished to form 85 an annular oil receptacle 20 and a raised hub portion, through which latter the threaded end 13 of the fuel pipe 12 is tightly screwed. The intermediate plate 17, in its upper surface, is dished to form an annular 90 oil-receiving channel 21.

It is now evident that when the elements 15, 16 and 17 are assembled as just described, they will be held in axial alignment by engagement, the one with the other, 95 and the nest will be held axially aligned with the hub 10 and bowl 9, by the fuel pipe.

The fuel pipe 12, instead of being made a continuous pipe, is preferably cut transversely in two at 22 and the adjacent threaded ends of the two pipe sections are independently screwed into the hub 10. This permits the main section of the pipe 12 to be first attached to the hub 10 and the 105 pipe section of the desired length thereafter

used to assemble the several generating plates, which, as already stated, may vary in number.

The operation of the burner described is substantially as follows:

The oil or fluid fuel overflowing from the upper end of the fuel pipe 12 will run into the dished surface of the upper plate 16, and if not before vaporized, will overflow and run down into the dished surface of the intermediate plate 17 and from thence will overflow and run down into the dished surface of the lower plate 15, and, of course, if there is still unvaporized oil, it will run to the bottom of the bowl 9. However, when the burner is in action, the said elements 15, 16 and 17 will be at such temperature that vaporization of the oil will be very rapid, so that there will seldom be any oil that will reach the bottom of the bowl. Only at times will the unvaporized oil reach the dished surface of the lower plate 15. Of course, when the burner is in action, the air intake tube 5 will be subject to the flame and kept at high temperature so that the air delivered at the point of combustion will be superheated and will assist in the rapid vaporization of the oil. The vaporized oil will be commingled with the air as the air passes in an annular stream completely around the generating plates, and the commingled air and oil will be delivered downward and outward in a sort of an inverted umbrella-shaped blast and will be carried against and between the pins or projections 11. From the statements just made, it will be understood that it is highly important that at least the uppermost generating plate be located upward within the delivery end 40 of the air tube. Preferably, both the rims of both the upper and intermediate plates 15 and 17 are located within the delivery end of the air tube, so that there is provided in the air delivery tube two contractions, and 45 between said contractions an expansion or

increase of the conducting capacity in the annular air passage. This arrangement causes the air to move under increased velocity as it passes the rims of said upper and intermediate generating plates, and thus to wipe up the oil from the edges of the said plates.

The flame will, under usual conditions, be outward of the bowl and of the pins 11, but the said bowl and pins, because of the high temperature within the combustion chamber, will be kept hot enough to very greatly assist in the thorough commingling of the air and oil vapors and the generation thereof into a more gaseous form, so that the combustion, when it takes place, will be very rapid, intense, and complete.

The efficiency of this burner has been thoroughly demonstrated in practice.

What I claim is:

1. An oil burner comprising a bowl having a raised rim and a raised central hub, an air delivery tube, the delivery end of which is located above said bowl and is concentric to the projected axis of the hub thereof, a stack consisting of upper, lower and intermediate generating plates, said generating plates having dished annular surfaces, said lower plate having a raised tubular hub upon which the intermediate and upper plates are seated, and an oil delivery pipe extended upward through the hub of said bowl and passed axially through said upper generating plate to the central top portion thereof.

2. The structure defined in claim 1 in which the upper generating plate is within the delivery end of said air tube.

3. The structure defined in claim 1 in which said bowl inward of its rim and outward of said stack of generating plates is provided with projecting pins.

In testimony whereof I affix my signature.

CLARENCE A. BERKINS.
